UNITED STATES PATENT OFFICE

ARTHUR HERBERT CURTIS, OF BEDFORD, ENGLAND

ELECTRICAL PLUG CONNECTER

Application filed July 30, 1927, Serial No. 209,421, and in Great Britain August 5, 1926.

The invention relates to electrical plug connectors. The type of plug at present most commonly used for making semi permanent connections to socket bearing apparatus such for example as high tension batteries, have been found to suffer from the effect that good contact is frequently not made between the plug and its cooperating socket. This is due in a large measure to the fact that the depths of the sockets vary considerably and also to the fact that the interior contact surface of the socket sometimes becomes coated with insulating compound, grease, or the like.

It has been proposed to overcome the latter difficulty by the use of a substantially conical plug having a spirally disposed gripping edge, but the objection to this plug is that owing to its conical structure unless the socket is of the full and correct depth it makes very uncertain contact.

The object of the present invention is to provide a plug which shall overcome both the above difficulties in a simple manner and the invention consists broadly in the arrangement according to which the plug comprises a metallic strip with reduced end portions, said strip being bent upon itself so that said reduced end portions lie more or less parallel side by side and form the plug proper.

In order that the invention may be more clearly understood a plug in accordance with the invention will now be described, reference being made to the accompanying drawings, wherein:

Fig. 1 is a side elevation of said plug.

Fig. 2 is a sectional side elevation of the same.

Fig. 3 is a plan of the same.

Fig. 4 is an under plan of the same, and

Fig. 5 is a side elevation of a slight modification of the same.

Thus said plug comprises a strip of metal 45 1 bent to the form of a long rectangular U.

The strip is reduced for a space adjacent each of its two ends and the strip is bent so that the two reduced portions 1a thus formed lie closer together than the remaining portions of the arms of the U. These 50 two reduced portions constitute the more or less parallel pieces above referred to. By pressing the arms of the U towards each other said reduced portions may be inserted into a complementary socket and upon removing such pressure they will press outwardly against the inner wall of the socket, thus making good electrical contact. It should be noted that even if said reduced portions enter the socket for only part of 55 their length good and sufficient contact is obtained.

A hole is provided through the portion 1b of the U connecting the two arms thereof, and through this hole from the inside 60 is passed a terminal screw 2 which screws into engagement with a terminal nut 3 of insulating material at the outside. The screw 2 is formed with a concentric through hole 2a and the outer end of the terminal 65 nut 3 is formed with an outwardly expanding concentric hole 3a somewhat larger than, and constituting a continuation of, said hole 2a.

It will thus be seen that the hole 2a constitutes a socket in electrical connection with the plug portions 1a so that a number of the plugs may be plugged one on top of the other. The head 2b of the terminal 70 screw 2 may be rectangular and adapted to clamp the lead against the said portion 1b of the U.

The reduced portions 1a of the U strip 75 1 are substantially arcuate in cross section with their concave faces outwards whereby cutting edges are formed so that upon insertion of the plug into the socket and rotation of the former any insulated deposit 80 upon the walls of the latter is scraped away 85

and a clean metallic surface is available for contact.

If desired a shroud of an insulating material, capable of being produced in different colours may be interposed between the terminal nut 3 and the U strip 1, as shown at 4 of Fig. 5, said shroud being also bent to fit the exterior periphery of said bent strip or the arms and portion 1b may be 10 coated with an insulating enamel of distinctive colour so as to provide an insulating surface by which the plug may be held.

It will be understood that the construction may be varied in a number of ways 15 without departing from the scope of the invention as defined in the appended claims. For example the part of the metallic strip lying between the reduced ends may be more or less circular instead of U shape.

20 What I claim and desire to secure by Letters Patent is:—

1. An electrical plug connector, comprising a metallic spring strip doubled upon itself in U-form to provide separated side portions, said separated side portions having relatively wide finger grip sections adjacent the bend of the U and narrow reduced end portions to enter a contact socket when the side portions are pinched together by means 25 of the finger grip sections aforesaid and a terminal screw extending through the connecting portion of the strip between the side portions, said terminal screw being of tubular form to provide a socket for the insertion of another similar plug connector 30 therein.

2. An electrical plug connector, comprising a metallic spring strip doubled upon itself in U-form to provide separated side 40 portions, said separated side portions having relatively wide finger grip sections adjacent the bend of the U and narrower reduced end portions to enter a contact socket when the side portions are pinched together by 45 means of the finger grip sections aforesaid, a tubular terminal screw on the connecting portion of the device between the side portions thereof and an insulating finger grip also on said connecting portion.

50 3. An electrical plug connector, comprising a metallic spring strip doubled upon itself in U-form to provide separated side portions, said separated side portions having relatively wide finger grip sections adjacent the bend of the U and narrower reduced end portions to enter a contact socket when the side portions are pinched together by 55 means of the finger grip sections aforesaid, a tubular headed contact screw extending up through the connecting portion of the strip between the side portions thereof and an insulating button threaded on the upper extended portion of the tubular screw.

60 4. An electric plug connector, of substantially U-form and having a substantially rec-

tangularly bent head portion with spaced resilient side arms, a terminal screw having an angular head beneath the rectangularly bent head portion of the device and a co-operating screw portion on top of the head portion of the device, and whereby a conductor wire may be secured to said head portion of the device, said terminal screw being of tubular form and of a size to receive the spring contact arms of another 75 similar plug connector.

In witness whereof I affix my signature.
ARTHUR HERBERT CURTIS.
